UNITED STATES PATENT OFFICE.

EMIL GRANTZOW, OF DRESDEN, GERMANY.

SHARPENING MACHINE FOR PENCILS AND OTHER STYLES.

Application filed March 13, 1924. Serial No. 698,953.

To all whom it may concern:

Be it known that I, EMIL GRANTZOW, a citizen of the German Republic, residing at Dresden, Germany, have invented certain new and useful Improvements in a Sharpening Machine for Pencils and Other Styles, for which I have filed an application in Germany on the 12th of March, 1923, and of which the following is a specification.

10 This invention relates to a sharpening machine for styles of any kind which may be adjusted according to whether the point has to be more or less sharp or blunt, means being provided for removing from the sharpener points which have broken off.

15 An embodiment of the invention is shown by way of example on the accompanying drawing in which:

Fig. 1 is a front elevation of the complete machine.

20 Figs. 2, 3, 4 and 5 show each certain elements or parts of the machine.

Fig. 6 is a rear view of the complete machine.

25 Fig. 7 is a cross section.

In the frame 1 of the machine a holder 2 for the collecting box for the waste material is arranged. On the machine frame 1 a cutting plate 3 is fixed by means of screws 4. This cutting plate 3 has in its upper edge two bearings 5 and it has further an oval aperture 6 extended at the lower end by a rectangular aperture 7. The edges of the aperture 6 are curved in outward direction and are sharp so that they form cutting edges. An element 8 forms together with the cutting plate 3 the funnel into which the pencil to be sharpened is inserted so that its part to be pointed projects

40 through the aperture 6. The element 8 is hooked with hooks 10 into the bearings 5 so that it can oscillate, a spring 11 serving for pushing the element 8 away from the plate 3. A holding claw 25 is pivotally mounted on the frame of the machine above the funnel and it has a toothed crown 26. An intermediate gear 27, the driving wheel 28 of which is mounted on a shaft 29, gears with the toothed crown 26. The shaft 29 carries further a handle 30 and a star-shaped knife 9.

45 In guides 12 on the machine frame a bow-shaped wire 13 is mounted so that it can be moved in longitudinal direction the curved part of the wire being bent slightly back. One end of wire 13 is bent to form

an eye 14 the other end 15 being slightly curved. The two arms of the bow-shaped wire 13 are connected with one another by a transverse wire 16, a spiral spring being wound around one arm of the wire 13 between the transverse wire 16 and the guide 12. This spring 17 presses the bow-shaped wire 13 in inward direction so that the curved part 15 of the wire presses the element 8 against plate 3. A two-armed lever 19 pivotally mounted on a pin 18 of the machine frame has a short longitudinal slit 20 in its inner arm, a stud 21 of an angular element 22 engaging with this slit 20. The angular element 22 is movably mounted in dove-tailed guides 23 on the rear side of the machine frame and it is braked by the action of a blade spring 24. The upper arm of the angular element 22 engages with the aperture 7 of the cutting plate 3 and serves to limit the insertion of the pencil. The pencil is inserted into the holding claw 25 so that it projects into the funnel 3, 8 and its front end protrudes from the aperture 6. When the shaft 29 is being rotated by means of the handle 30 the toothed wheel 28 and the star-shaped knife 9 are also rotated. The holding claw 25 is rotated from the toothed wheel 28 through the intermediary of the gear 27. The blades of the star-shaped knife 9 slide along the edges of the aperture and sharpen the part of the pencil which protrudes from the aperture. The upper arm of the angular element 22 forms thus a gauge for the shape of the point; the higher this angular element stands, the sharper becomes the point and the deeper it stands the longer and sharper becomes the point. The angular element 22 is adjusted with the aid of the two-armed lever 19 and it is secured in its adjusted position by the action of the spring 24.

50 When a point breaks off at the sharpening the bow-shaped wire 13 has to be pulled in the direction of the arrow whereby the element 8 is released and also the spring 11, which up to this moment had to remain inoperative owing to the greater force of spring 17. The spring 11 makes the element 105 oscillate and the broken off point can drop out.

I claim:

55 1. A sharpening machine for pencils or styles comprising in combination a guide funnel for the pencil to be sharpened composed of a stationary cutting plate having an

oval aperture extended at the lower end by a rectangular aperture and of a plate-like element oscillably mounted on said cutting plate, means for securely holding said oscillable element in contact with said cutting plate, a spring for making this oscillable element oscillate away from said cutting plate when the securing means are rendered inoperative, an angular element below said funnel serving as gauge for the point to be produced, and means for adjusting this gauge element in its position.

5 2. A sharpening machine for pencils or styles comprising in combination a guide funnel for the pencil to be sharpened composed of a stationary cutting plate having an oval aperture extended at the lower end by a rectangular aperture and of a plate-like element oscillably mounted on said cutting plate, a bow-shaped spring controlled wire for securely holding said oscillable element in contact with said cutting plate, a spring for making this oscillable element oscillate away from said cutting plate when the securing means are rendered inoperative, an angular element below said funnel serving as gauge for the point to be produced, a two-armed lever for regulating the position of this gauge element, and a spring stronger than that which controls said bow-shaped wire for securing the same in the working position.

10 15 20 25

ing as gauge for the point to be produced, and means for adjusting this gauge element in its position.

3. A sharpening machine for pencils or styles comprising in combination a guide funnel for the pencil to be sharpened composed of a stationary cutting plate having an oval aperture extended at the lower end by a rectangular aperture and of a plate-like element oscillably mounted on said cutting plate, a bow-shaped spring controlled wire for securely holding said oscillable element in contact with said cutting plate, a spring for making this oscillable element oscillate away from said cutting plate when the securing means are rendered inoperative, an angular element below said funnel serving as gauge for the point to be produced, a two-armed lever for regulating the position of this gauge element, and a spring stronger than that which controls said bow-shaped wire for securing the same in the working position.
